SHANK IRON FOR SHOES

Filed Nov. 28, 1927

UNITED STATES PATENT OFFICE

ALFRED F. DONOVAN, OF BOSTON, MASSACHUSETTS

SHANK IRON FOR SHOES

Application filed November 28, 1927. Serial No. 236,103.

Among the principal objects which the present invention has in view are: To provide a rigid shank iron for supporting the outside of the tread of the foot with means for permitting a glove-fit at the inner side of the foot; to provide such a shank iron with a rigid and wide spread head for controlling the bend of the shoe on lines perpendicular with the axis of the shoe.

10 Figure 1 is a top plan view of a shank iron constructed and arranged in accordance with the present invention, the outline of the wearing sole of the shoe being shown by the thin and shaded line, the inner sole usually disposed on top of the shank iron having been removed from the same and from the wearing sole.

20 Figure 2 is a side edge view of an inner sole, a wearing sole, and shank iron constructed and assembled in accordance with the present invention, the construction being shown partly in section.

25 Figure 3 is a schematic view showing in cross section the disposition of shank irons constructed and arranged in accordance with the present invention in its relation to the human foot and the shoe structure therefor.

30 As seen in the drawings, a shank iron having a horizontal flat body 8, has a laterally extended depressed head 9, and a flattened heel plate 10. The shank iron is constructed of relatively thin metal, and to reinforce and render rigid, the same, a ridge or rib 11 is formed, said rib being substantially coincident with the axis of the foot and of the wearing sole 12 of the shoe. The rib 11 being thus disposed and constructed, prevents the shank iron from bending from the said curve with which it is provided.

35 10 As seen best in Figure 2 of the drawings, the head 9 is flared laterally to brace the wearing sole 12 and to impart thereto a bending moment which shall be perpendicular to the axis and to the rib 11. The moment referred to corresponds with the forward edge 13 of the head 9. The head 9 is anchored to the insole 14 of the shoe by means of spurs 15. This anchorage establishes and maintains the relation between the shank iron and the insole 14.

The heel plate 10 as shown in the drawings is extended further than heel plates of the ordinary shank iron so that it functions later in the process of shoe construction as means for turning or clinching the nails which are 55 driven through the wearing sole and heel that is added thereto.

When employing a shank cut away at the inside of the shoe as shown best in Figure 1 of the drawings, the leather constituting the upper of the shoe as well as the insole and wearing sole, may be drawn and pressed upon the last to fill the hollow in the last at the inner side thereof. When the molded and stretched soles and upper are set in the process of manufacture, it will be found that there has been imparted to the shoe what is styled a glove-fit, and in other words, the leather hugs the inner side of the foot under the instep thereof. A comfortable support is thus 70 imparted to the fleshy part of the foot under the instep, while the longitudinal arch of the foot is preserved by the body 8 and the reinforcing ribs 11.

75 The head 9 serves as a receptacle or platform upon which rests a metatarsal arch supporting pad 16, as can be seen best in Figure 2 of the drawings. Spurs 15 engage the pads 16 retaining it firmly in position. The forward edge of the pad 16 is carried 80 beyond the edge 13 of the head 9, the leather from which the pad is usually formed being skived to a feather-edge. Any abrupt ridge that could be felt is thus avoided. At the same time the flexibility of the forward edge 85 of the pad 16 permits the soles 12 and 14 to bend on the line established by the edge 13, at the forward end of the head 9.

I claim:

1. A shank iron for shoes comprising a 90 substantially transversely horizontal body portion for disposal in service under the outer side of a shoe; a head offset from said body portion and laterally extended for disposal in service below the ball of the foot; a heel plate 95 laterally extended beyond said body for disposal in service below the heel of the foot; and a reinforcing rib extending between said heel plate and said head, said rib being formed from the edge of said body portion 100.

adjacent the inner side of the shoe, and on substantially the axial line of the shoe.

2. A shank iron as characterized having a longitudinal arched body, said body portion having at one edge thereof, a relatively heavy reinforcing rib, said rib adapted to be disposed in service on a line substantially coincident with the longitudinal axis of the shoe.

3. A shank iron as characterized having a longitudinal arched body, said body portion having at one edge thereof, a relatively heavy reinforcing rib, said rib adapted to be disposed in service on a line substantially coincident with the longitudinal axis of the shoe; and a head offset from said body and connected with said rib, said head being forwardly flared and having a straight forward edge, said edge being substantially perpendicular to said rib for controlling the walking flexure of the shoe in which the shank is incorporated.

ALFRED F. DONOVAN.
